DESCRIPTION

FIG. 1 is a perspective view of a tire showing my new design; FIG. 2 is a front view thereof, for which the rear view is the same;

FIG. 3 is a top plan view thereof, for which the bottom plan view is the same;

FIG. 4 is a right side view thereof, for which the left side view is the same;

FIG. 5 is a cross-sectional view taken along line 5-5 in FIG. 2 and line 5'-5' in FIG. 4; and,

FIG. 6 is an enlarged sectional view taken along line 6-6 and line 6'-6' in FIG. 2.

The broken lines in the Figures depict environmental subject matter and form no part of the claimed design.
